AUTOMATIC STARTING DEVICE FOR
INTERNAL COMBUSTION ENGINESLloyd M. Williams, Oak Park, Ill., assignor, by
mesne assignments, to Lloyds Mfg. Co., Chi-
cago, Ill., a corporation of Illinois

Application September 24, 1928, Serial No. 308,018

44 Claims. (Cl. 290—38)

This invention relates to an electrically energized system controlling the starting motor of an internal combustion engine, for instance, an engine used in an automobile, and particularly 5 a system so arranged that upon the mere act of voluntarily closing a switch (for instance, the ignition switch) and releasing into the system electrical energy from an independent source, the starting motor will be energized and commence to crank the engine, and this condition will continue until the engine is running under its own power, whereupon the supply of current to the starting motor from the independent source will be automatically interrupted, but the 10 starter circuit will be in such condition that should the engine stall, the starting motor will automatically be re-energized and caused to repeat the starting operation.

Systems as heretofore designed for accomplishing the foregoing purpose have generally involved the principle of having the starter circuit open and the starting motor deenergized by some single function of the apparatus, for instance, the spinning of the starting motor after 15 being kicked out by attainment of self-propulsion in the engine or by the action of current from the generator which the engine drives, or even by a vacuum switch responsive to or reflecting the condition of suction in the fuel supply manifold of the engine. But all of these attempts 20 are believed to have failed because of unreliability of the circuit opening influence depended upon in each instance, the spinning of the kicked out starting motor alone requiring an impracticable 25 delicacy of adjustment in the relay in the circuit of the starting motor; the engine driven generator being too inconstant in its output at the time of starting, for instance, under the slow turn-over of a cold engine in the wintertime as 30 compared with quick turn-over in hot weather; and the manifold suction control being wholly unreliable as a reflection of the condition of the engine.

The primary object of the present invention 35 is to provide a more reliable automatic starting motor circuit control for systems of the kind described, and particularly a system in which the opening of the starting motor circuit is responsive not to a single function of the apparatus, but 40 to two functions thereof, one of which reflects the condition of the starting motor having been kicked out of drive by the self functioning of the engine, for instance, the spinning which momentarily occurs in the starting motor upon losing 45 its mesh with the fly-wheel, and the other of

which reflects the condition of the turning over of the engine, for instance, the suction which it creates in the fuel feed manifold; the first function, however, being dominant over the second function, with the result that while the second 5 function may have been set up as a starting motor circuit-opening influence as soon as the motor begins to turn over, it will not accomplish its purpose of opening the starting motor circuit until the starting motor, by the attainment of 10 self propulsion in the engine, has been thrown out and signifies that starting has been successfully accomplished; at which time the influence of the starting motor over its own circuit will fall to such a point that the second function or 15 manifold suction will be free to enter into play. To attain this object, there is provided in the starting motor circuit not only a circuit closer that is responsive to the voluntarily closed ignition or starting circuit, but a second circuit closer 20 which is influenced in the direction of closing the starting motor circuit by the dominant primary control furnished by the starting motor, and in the direction of opening said circuit by the secondary influence derived from the manifold suction; the preferred embodiment of this 25 part of the invention involving two electro-magnets operating in opposite directions upon the starting motor circuit breaker, namely, a circuit closing magnet and a circuit opening magnet, the 30 winding of the circuit closing magnet being in circuit with the starting motor, the winding of the circuit opening magnet being in circuit with a switch that is actuated by the manifold suction, and both magnets being energized by current 35 from the common source so that the circuit opening magnet becomes effective not only by reason of the drop in current demand of the starting motor, but by reason of increased current which reaches it from the source when the demand of 40 the starting motor fails. The starting motor circuit breaker is biased through means of a spring, or otherwise, to normally assume circuit closing 45 position so that as long as the voluntarily controlled or ignition circuit is left closed, on failure of the secondary controlling function (the manifold suction) signifying the interruption of the running of the motor, the cycle of starting functions automatically repeats itself. In other 50 words, the engine is self starting as often as it stalls, provided the ignition switch is left closed.

Other objects of the invention relate to the provision of suitable instrumentalities for use in successfully realizing the main object of the 55

invention, and will appear from the following description.

In the accompanying drawing, in which the preferred embodiment of the invention is shown by way of illustration—

Figures 1, 2, and 3 are, respectively, a plan view, a side elevation, and an end elevation of the group of electro-magnetically controlled interlocking switches employed in the system.

Figure 4 is a schematic view showing the operating circuits of the system along with the co-ordinated ignition circuit for the internal combustion engine, an auxiliary voluntarily actuated switch which may be used for retiring the starting device when it is desired to test the ignition circuit, and the suction switch of the second relay magnet, which is associated with the intake manifold of the engine.

Referring to Figure 4, 1 indicates the starting motor of the power plant of an automobile or other internal combustion engine; 2 an automatic starting motor switch in circuit with said motor; 3 a starting motor switch magnet controlling the switch 2; 4 the conventional ignition switch which in the present invention is employed for also releasing electrical energy to the starting motor switch; 5 a make and break or relay controlling the circuit of the motor switch magnet 3; 6 an armature controlling the make and break 5 which is biased through means of a spring 6a toward its circuit closing position; 7 the motor energizing actuator in the form of a first relay magnet which is in the circuit of starting motor 1 and switch 2 and is related to the armature 6 in a manner to cooperate with the spring 6a in keeping the make and break 5 closed; 8 the motor arresting actuator in the form of a second relay magnet related to the armature 6 in a manner to adapt said magnet to open the make and break 5 in opposition to the spring 6a when there is a sufficient drop in the attractive force of the first relay magnet 7 and consequent rise in the force of magnet 8 to permit this to be done, and which forces in their relation one to the other while primarily a function of the speed of the starting motor may also be influenced through means of the stop screw 6b which determines the air gap or spacing of the ends of the armature 6 from the respective magnets; and 9 represents the suction switch which is held normally open by means of the balancing springs 10 on opposite sides of its controlling piston 11 and which keeps the second relay magnet 8 deenergized so long as the engine is not running, but which suction switch closes the third or parallel battery circuit through magnet 8 as soon as the starting motor commences to turn the motor over and remains closed as long as the motor is running. To accomplish the last-named function, the cylinder 12 of said switch is tapped into the fuel mixture manifold 13 of the engine which is to be controlled. 14 represents the terminal of the motor arresting actuator magnet circuit which is grounded by the depression of switch 9 through the piston 11, cylinder 12, and ground connection 15. 16 represents an independent source of electrical energy, usually existing in the form of a storage battery as the supply of current for ignition in the engine and for driving the starting motor. In addition to the elements just enumerated, the system will preferably include a conventional ignition coil schematically indicated at 17, in position to be controlled by the same switch 4 which controls the starting device, also the usual distributor 18 and an independent ground connection 19 for the ignition circuit; also an independent manually controlled switch 20 interposed between the starting switch magnet 3 and a suitable ground connection 31a so that the starting motor can be cut out when desired, for instance, when it is desired to test the ignition device.

An important feature of the preferred embodiment of the invention resides in the separate and independent nature of the battery circuits employed and particularly the circuit that connects the battery with starting motor 1, the circuit that connects the battery with motor switch magnet 3, and a circuit which connects the battery with the relay opening magnet 8 and engine 15 actuated switch 9, as suggested by the separate and independent ground connections and one or more controlling switches in each of them, as will appear from the following. The circuit which includes the starting motor, switch 2, and first 20 or motor energizing relay magnet 7, starting from the independent electrical source 16, is represented by wire 21, switch 2, wire 23, first relay magnet 7, wire 25, starting motor 1, and independent ground connection 26, from which it will appear 25 that whenever motor switch magnet 3 is energized and motor starting switch 2 is closed, first relay magnet 7 will be energized and will (initially) hold the armature 6 in position to close the make and break 5. The circuit of the starting switch magnet 3 is traced from the source 16, through wire 21, wire 27, ammeter 28 (incidentally), ignition switch 4, wire 29, starting switch magnet 3, wire 30, make and break 5, wire 31, starting motor cut out switch 20, and ground 31a, 35 from which it will be seen that when the ignition switch 4, which is a manually controlled switch, is closed, magnet 3 will be energized and starting switch 2 will be closed; hence, closing of the ignition switch 4 energizes the starting 40 motor 1 to cause it to operate the engine, and it will continue to operate the engine until the circuit of magnet 3 is opened at the make and break 5 of the relay. The circuit of the second or motor arresting relay magnet 8, the function 45 of which is to swing the armature 6 to open the make and break 5, is traced from existing current source 16, through wire 21, wire 33, second relay magnet 8, wire 34, suction switch 9, terminal 14, piston 11, cylinder 12, and ground connection 15. 50 From this it will be seen that the circuit of second relay magnet 8 is wholly independent of the circuit of starting motor 1 as well as the ignition circuit 17, 18, 19, and said second relay magnet will not be influenced in any way by either of 55 these other circuits. Hence, the starting switch 2 will remain closed until starting motor 1 has succeeded in bringing the engine to self-propulsion, and the starting motor has been kicked out of gear and left free to spin; and such spinning causes such a drop in current demand passing through first relay magnet or circuit closing magnet, as to leave the approximately full battery current to raise the strength of the second or motor arresting relay magnet 8, and to leave 60 magnet 8 (now that its circuit is being held closed by suction switch 9) free to actuate armature 6 and open the starting motor switch actuating circuit at 5. And in so arresting the starting motor, the system remains in the last stated condition so long as manual ignition switch 4 remains closed and suction sufficient to hold down the switch 9 continues in the manifold 13. Should the ignition switch 4 be opened and the ignition circuit 17, 18, 19 interrupted so that the engine 7

stops, vacuum in manifold 13 is relieved, switch 9 is lifted, magnet 8 is deenergized, make and break switch 5 returns to closed position under influence of spring 6a, and the system is ready to 5 be again called into play by manually closing the ignition switch 4. So long, however, as manual ignition switch 4 is left closed, the system remains automatically re-starting, because should the engine stop as a result of stalling while ignition 10 switch 4 remains closed, relief of the vacuum in manifold 13 and consequent raising of the switch 9 deenergizes second relay magnet 8, permitting make and break 5 to close, the starting motor switch magnet 3 will be re-energized to close the 15 starting switch 2, and thus the system automatically re-starts the motor without any voluntary act on the part of the driver, and this occurs with such promptness as to relieve the hazard of the stalling engine even though the occurrence be 20 upon a railroad crossing or other place of danger.

An important feature of the preferred embodiment of the invention resides in the nature of the windings of the two magnets 7 and 8. The circuit of the starting motor 1 which passes 25 around magnet 7 would naturally be of a dimension which carries very high amperage to the starting motor from the current source 16 and lends considerable strength to the magnet 7 at the instant of starting, thus supplementing the 30 spring 6a on armature 6 and even weakening, by its excessive current consumption, the force of the opening magnet 8, and thereby avoiding any vibration or fluctuation at the make and break 5, upon which starting switch magnet 3 is de- 35 pendent; but the instant the starting motor 1 spins under drive of the motor or by being thrown out and left unrestrained under its own driving current, there will be such a material drop in amperage reaching the starting motor through 40 the relatively short and coarse winding on magnet 7 as to largely relieve the attractive force of said magnet and leave the armature of the relay ready to respond very promptly to the second 45 relay magnet 8. Second relay magnet 8 is wound for high voltage; that is to say, it has a relatively 50 long, fine winding. Besides, it is deprived of current largely when starting motor 1 is first thrown in and supplied with greater current when the starting motor spins, so that it develops ample 55 strength (switch 9 being closed) to throw the armature 6 in position to open the make and break 5. The different characters of winding employed on the magnets 7 and 8 are suggested in Figure 2, where winding 7 is indicated as two 60 broad convolutions or bands of conductor 23 passing from magnet 7 to the armature 2a of the switch 2, where said conductor is in electrical contact with said armature; whereas the winding on magnet 8 is conventionally represented as a built up helix of wire 33.

In Figures 1 to 3 the elements which are mechanically developed are indexed by the same reference characters as in Figure 4, where they are merely schematically developed, and the binding posts for the several circuit wires in Figures 65 2 and 3 are indicated by the reference numbers which the wires bear in Figure 4 plus the exponent "a."

To prevent spasmodic or fluctuating action of 70 and delay-action or lost motion in switch 9, said switch includes, in addition to its binding post 9a which receives a wire 34, grounded contact terminal 14 and bridging movable contact 9b, an insulating facing washer 9c and a spring 9d confined between facing washer 9c and a facing

washer 9e under the terminal member 14, so that whenever the bridging member 9b is free from the lifting influence of piston 11, the spring 9d will seat it upon and establish electric contact with the terminal 14; said switch comprising in 5 addition to its piston 11, a stem 11a with a shouldered upper end 11b which extends through the bridging contact 9b and through means of which the piston may pick up and lift the contact 9b from the terminal 14 whenever piston 11 is 10 free from suction in manifold 13 and surrendered to the influence of balancing springs 10; the delay-action element of switch 9 resulting from the fact that the piston 11 is drawn downwardly 15 a distance materially greater than that which is sufficient to permit the bridging contact 9b to reach the terminal 14, so that the piston has to execute a substantial portion of its upward movement, upon relief of the suction manifold 13, before it begins to unseat the contact 9b; moreover, a restricted vent 12a for escape of air from the space above the piston 11 during upward movement of the piston, renders the upward movement of the piston rather sluggish. Hence, if there should be a back-fire or sudden temporary rise in pressure in the manifold 13 other than that which is incident to a definite stopping of the engine, the switch 9 would not respond sufficiently to break the circuit of the second 20 relay magnet 8, and therefore would not momentarily energize the starting motor at an undesirable time; but the said switch 9 will be held closed by the spring 9b, under such circumstances, for a brief space of time sufficient for suction 25 in the manifold 13 to be recovered. In other words, switch 9 has embodied in its construction and operation a delay-action element that prevents it from being too sensitive to temporary fluctuations of pressure in the manifold 13.

In assembling the parts of the switch 9, a fiber 40 or other non-conducting housing 14a conforming to the terminal piece 14 may be threaded to the cylinder 12, with an insulating disk 14b between the parts 14 and 12.

I claim:

1. In combination with an internal combustion engine, a starting motor constructed to drive said engine, a starting motor circuit including said motor, a switch controlling said starting motor circuit, a switch-closing actuator and a 50 switch-opening actuator both acting upon said switch, one in opposition to the other, the switch-closing actuator being under control of the starting motor, and means for energizing the switch-opening actuator constructed for connection with 55 and adapted to respond to a running function of the engine; the switch-closing actuator being constructed to dominate the switch-opening actuator in the initial operation of the starting motor but yielding to the switch-opening actuator after the engine has been set in motion.

2. In combination with an internal combustion engine, a starting motor constructed to drive said engine, a starting motor circuit including said motor, a switch controlling said starting 65 motor circuit, a switch-closing magnet and a switch-opening magnet both acting upon said switch, one in opposition to the other, the switch-closing magnet being responsive to current flowing through the starting motor, a circuit including said switch-opening magnet, and a switch controlling the last-named circuit having means for connecting it with and adapted to respond to a running function of the engine; said switch-closing magnet being constructed to dominate 70

75

the switch-opening magnet in the initial operation of the starting motor but yielding to the switch-opening magnet when the engine has been set in motion.

5 3. In combination with an internal combustion engine, a starting motor constructed to drive said engine, a starting motor circuit including said motor, a switch controlling said starting motor circuit, a switch-closing magnet and a switch-opening magnet both acting upon said switch, one in opposition to the other, the switch-closing magnet being in circuit with the starting motor, and an engine actuated switch in circuit with said switch-opening magnet constructed to respond to 10 a function of the engine which is set up by the operation of the starting motor; said switch-closing magnet being constructed to dominate the switch-opening magnet in the initial operation of the starting motor but yielding to the switch-opening magnet after the engine has been set in motion.

4. In an automatic starting device for internal combustion engines, a starting motor having means through which to connect it with an engine 25 to be started, a source of electrical energy, a motor circuit including said source and said motor, a motor switch controlling said motor circuit, a motor switch magnet controlling said motor switch, a motor switch magnet circuit connecting 30 said motor switch magnet with said source, a voluntary circuit closer controlling the last named circuit, and means controlling said motor switch magnet circuit comprising a normally closed make and break included therein, a first relay magnet 35 included in the motor circuit and adapted to govern the opening movement of said make and break, a second relay magnet adapted to open said make and break, and a second relay magnet circuit connecting said second relay magnet with 40 said source, also having a make and break.

5. An automatic starting device for internal combustion engines as described in claim 4, in which the first relay magnet is wound to cause it to act upon the make and break under the influence of high amperage in the motor circuit, and release said make and break when the amperage in the motor circuit is lowered by the running of the motor, and the second relay magnet is wound to render it responsive to high voltage in its circuit.

55 6. An automatic starting device for internal combustion engines as described in claim 4, in which the second relay magnet circuit includes a circuit closer having means adapting it to respond to a running condition of an engine to be started.

7. An automatic starting device for internal combustion engines as described in claim 4, in which the second relay magnet circuit includes a circuit closer, a suction piston controlling said 60 circuit closer, and means whereby said suction piston may be exposed to the suction of an engine to be started.

8. An automatic starting device for internal combustion engines as described in claim 4, in which the second relay magnet circuit includes a 65 normally open circuit closer, means adapted to respond to a function of an engine for closing the same, and a delay-action device retarding the opening of said circuit closer when said circuit closer is not influenced by the engine.

9. An automatic starting device for internal combustion engines as described in claim 4, in which the second relay magnet circuit includes a 70 normally open circuit closer, means whereby said

circuit closer may be made responsive to a running function of an engine, a piston moving with said circuit closer in the direction of opening, and a cylinder enclosing said piston and partially confining a fluid medium in relation to resist and 5 slow down the movement of the circuit closer to open position.

10. An automatic starting device for internal combustion engines as described in claim 4, in which the second relay magnet circuit includes a 10 normally open circuit closer adapted to respond to a running function of an engine, and means whereby upon interruption of the running function of the engine, which influences said circuit closer, closure of said circuit is continued during 15 the initial portion of the movement of the circuit closer to open position.

11. An automatic starting device for internal combustion engines as described in claim 4, in which the motor switch magnet circuit includes a 20 manually controlled interrupting switch which is free from influence on the second relay magnet circuit.

12. An automatic starting device for internal combustion engines as described in claim 4, in which the motor circuit and the motor switch magnet circuit have independent ground or return connections.

13. An automatic starting device for internal combustion engines as described in claim 4, in which the motor circuit and the second relay magnet circuit have independent ground or return connections.

14. An automatic starting device for internal combustion engines as described in claim 4, in which the motor switch magnet circuit and the second relay magnet circuit have independent ground or return connections.

15. An automatic starting device for internal combustion engines as described in claim 4, in which there is an engine ignition circuit branching from the motor switch magnet circuit and controlled by the voluntary circuit closer therein, but having its own independent ground or return connection and free from other influences of said 45 motor switch magnet circuit.

16. An automatic starting device as described in claim 4, in which said first and second relay magnets have a common armature attracted alternately by the respective magnets, and said armature has an adjustable stop limiting its approach to one of said magnets and thereby regulating the initial attraction of the other magnet for said armature.

17. In an automatic starter for internal combustion engines, a source of electrical energy, an electric starting motor adapted for cranking connection with an engine, a motor circuit supplying current from said source to said motor, a relay adapted to make and break said motor circuit and thereby energize and arrest said motor, said relay including a first actuator normally moving it to position to energize the motor, and an electromagnetic second actuator which, when sufficiently energized, moves the relay to position to arrest the motor, and a circuit delivering from said source, to said second actuator, current which does not pass through the motor; said second actuator being constructed to exert upon said relay, during large current consumption by the motor, a minor force that leaves the first actuator dominant and, under reduced current consumption by the motor, a major force that overcomes said first actuator and arrests the motor, there being means responsive to a running function of 75

- the engine adapted to continue the electro-magnetic second actuator in energized condition and thereby hold open the motor circuit, so long as the engine continues to run.
- 5 18. An automatic starter as described in claim 17 in which the last named means includes a switch located in the circuit through which the second actuator is energized.
- 10 19. In an automatic starting mechanism for internal combustion engines, a starting circuit including an electro-magnetic starting switch, a control circuit for said starting switch including circuit making and breaking means, means responsive to the cranking load for maintaining the 15 making and breaking means closed during cranking, and fluid pressure operated means responsive to rotation of the engine for opening said making and breaking means when the engine starts.
- 20 20. In an automatic starter for internal combustion engines, a source of electrical energy, an electric starting motor adapted for cranking connection with the engine, a starting motor circuit supplying current from said source to said starting motor, a make-and-break for closing and 25 opening said starting motor circuit, and a relay adapted to close and open said make-and-break and thereby energize and arrest said motor; said relay including a first actuator normally moving it to the position to close the starting motor circuit, and a second actuator energized subsequently to the closing of the make-and-break and independently of current passing therethrough, and adapted to impose upon said relay a force in the direction to open the starting motor circuit 30 when the engine is operating under its own power; the force imposed upon the relay by said second actuator being inferior to the force imposed thereon by the first actuator during cranking movement, but superior thereto when the engine is 35 operating under its own power.
- 40 21. In an automatic starting mechanism for internal combustion engines, a starting motor constructed to drive said engine, a source of electrical energy, a starting motor circuit including a starting motor-switch, switch-closing means responsive to the starting motor for maintaining the starting motor-switch closed during cranking, and switch opening means responsive to rotation of the engine for opening said motor-switch independently of current from any second source of 45 electrical energy and independently of current passing through said motor-switch, when the engine starts.
- 55 22. An automatic starting device for internal combustion engines as described in claim 1, in which the means for energizing the switch-opening actuator acts to set up a minor force and a major force, the minor force being inferior to the force set up in the switch-closing actuator during the initial operation of the starting motor in cranking the engine, the major force operating to open said switch and arrest the starting motor after the engine has obtained self-operation.
- 60 23. An automatic starting device for internal combustion engines as described in claim 1, in which the switch-closing means includes an electro-magnetic coil, said coil being connected in series with the starting motor.
- 65 24. In an automatic starting device for internal combustion engines as described in claim 1, in which is included means for maintaining said switch in a normally closed position, a second normally opened switch to also control the said 70 motor circuit, an electro-magnetic coil connected 75
- to operate said last mentioned switch, a control circuit including said coil and said first mentioned switch and a normally open manually operated switch.
- 5 25. An automatic starting device for internal combustion engines as described in claim 1, in which the means for energizing the switch-opening actuator includes a compartment having a yielding member, engine actuated means for setting up a force on the inside of said compartment, said yielding member being adapted to respond to the force set up on the inside of said compartment and acting to energize the switch-opening actuator to open the said switch.
- 10 26. An automatic starting device for internal combustion engines as described in claim 1, including adjustable means to regulate the forces set up in the switch-closing actuator in relation to the forces set up in the switch-opening actuator.
- 15 27. In an automatic starting device for internal combustion engines as described in claim 1, in which is included means for maintaining said switch in a normally closed position, a second normally opened switch to also control the said motor circuit, and in which the means for energizing the switch opening actuator includes a compartment, said compartment having a yielding member, said yielding member being located between the interior of said compartment and said first mentioned switch, engine responsive means for setting up a force on the inside of said compartment, said yielding member being adapted to respond to the force set up on the inside of said compartment and operating to energize the 25 switch opening actuator to open said first mentioned switch.
- 30 28. In an automatic starting device for internal combustion engines as described in claim 1, in which is included means for maintaining said switch in a normally closed position, a second normally open switch to also control the said motor circuit, and delay action means acting to delay the closing of said first mentioned switch when the engine ceases to operate under its own power.
- 35 29. In an automatic starting device for internal combustion engines as described in claim 1, in which is included means for maintaining said switch in a normally closed position, a second normally open switch to also control the said motor circuit, delay action means including a compartment which partly confines a fluid medium acting to delay the closing of said first mentioned switch when the engine ceases to operate under its own power.
- 40 30. In an automatic starting device for internal combustion engines as described in claim 1, in which is included means for maintaining said switch in a normally closed position, a second normally open switch to also control the said motor circuit, and delay action means including a movable member, said delay action means acting, upon interruption of the self operation of the engine, to delay the closing of said first mentioned switch during the initial portion of the 45 movement of said movable member.
- 55 31. In combination with an internal combustion engine, a starting motor constructed to drive said engine, a starting motor circuit including said starting motor, a motor-switch controlling said starting motor circuit, a relay for opening and closing said motor-switch including two relay switches, one of which is normally closed and the other normally open, means responsive to the starting motor for operating one of said switches,

and means responsive to the engine for operating the other switch.

32. An automatic starting device for internal combustion engines as described in claim 31, in which the means responsive to the engine includes a compartment having a yielding member, and means for setting up a force on the inside of said compartment, connected with and adapted to respond to a running function of the engine, said yielding member being operatively connected with the relay switch which is responsive to the engine.

33. In combination with an internal combustion engine, a starting motor for cranking said engine, a driving connection for the starting motor including a driving gear adapted to mesh with and demesh from a driven gear connected to the fly wheel of the engine, operating means and stopping means to control the movement of said driving connection, the force of one means opposing the force of the other, the operating means being under control of the starting motor, means for energizing the stopping means constructed for connection with and adapted to respond to a running function of the engine, the operating means being constructed to set up a force to dominate the stopping means during the initial operation of the starting motor in cranking the engine but yielding to the stopping means after the engine is self operating.

34. An automatic starting device for internal combustion engines as described in claim 33, in which the operating means includes a coil connected in series with the starting motor.

35. An automatic starting device for internal combustion engines as described in claim 33, in which the stopping means has a coil connected in shunt with the starting motor, an electrical circuit for said coil, and a circuit closer for said electrical circuit, said circuit closer being under control of the engine.

36. In an automatic starting device for internal combustion engines, a source of electrical energy, an electric starting motor adapted for cranking connection with an engine, a starting motor circuit supplying current from said source to said motor, a starting motor-switch for said circuit, an electro-magnetic coil to operate said starting motor switch, a circuit connecting said coil to a source of electrical energy, a relay make-and-break for the last named circuit, a relay armature to operate said relay make-and-break and thereby energize and arrest the starting motor, a first actuator acting to hold said relay armature in a position to energize the motor, an electromagnetic second actuator which, when sufficiently energized, moves said relay armature to position to arrest the motor, and a circuit delivering from said source to said second actuator current which does not pass through the motor; said second actuator being constructed to exert upon said relay armature, during large current consumption by the motor, a minor force that leaves the first actuator dominant and, under reduced current consumption by the motor, a major force that overcomes said first actuator and arrests the motor, and including delay-action means acting to retard the closing of said relay make-and-break when the engine ceases to operate under its own power.

37. An automatic starting device for internal combustion engines as described in claim 36, in which the delay action means includes a compartment which partly confines a fluid medium acting to delay the closing of said relay make and break when the engine ceases to operate under its own power.

38. An automatic starting device for internal combustion engines as described in claim 36, in which the delay action means includes a movable member, said movable member operating, upon interruption of the self-operation of the engine, to delay the closing of said relay make-and-break during the initial portion of the movement of said movable member to a position to operate 15 to close said relay make-and-break.

39. An automatic starting device for internal combustion engines as described in claim 36, in which the delay action means includes a spring operated movable member operating, upon interruption of the self-operation of the engine, to delay the closing of said relay make-and-break during the initial portion of the movement of said movable member to a position to close the said relay make-and-break. 25

40. An automatic starting device for internal combustion engines as described in claim 36, in which the first actuator includes a coil connected in series with the starting motor.

41. An automatic starting device for internal combustion engines as described in claim 36, in which the first actuator is electro-magnetic in character and is energized by current drawn by the motor from the same source that energizes the second actuator independently of the motor, 35 the magnet of the first actuator being wound for high amperage, and the magnet of the second actuator being wound for high voltage.

42. An automatic starting device for internal combustion engines as described in claim 36, including means for maintaining the motor switch open and the starting motor arrested as long as the engine is self operating. 40

43. An automatic starting device for internal combustion engines as described in claim 1, in which the switch closing actuator and the switch opening actuator both act upon said switch by pulling on a movable member, said movable member being operatively connected with one contact of said switch, and in which the switch opening actuator is constructed so that, when energized, it operates to exert a minor pull on said movable member during the initial operation of the starting motor in cranking the engine and, when the engine becomes self operating, it then operates 50 to exert a major pull on said movable member; said major pull operating to pull said movable member to a position to open said switch and arrest the starting motor. 55

44. In an automatic starting mechanism for internal combustion engines, a starting motor constructed to drive said engine, a starting motor circuit including a starting motor-switch, switch-closing means responsive to the starting motor for maintaining the starting motor-switch closed 60 during cranking, switch-opening means, and means for energizing the switch-opening means constructed for connection with and adapted to respond to a running function of the engine. 65
